J. ISBISTER AND J. CHAPMAN,

HATPIN.

APPLICATION FILED JULY 12, 1918.

1,368,155.

Patented Feb. 8, 1921.

FIG.1

FIG.2

FIG.3

UNITED STATES PATENT OFFICE.

JOHN ISBISTER AND JAMES CHAPMAN, OF DUNEDIN, NEW ZEALAND.

HATPIN.

1,368,155.

Specification of Letters Patent.

Patented Feb. 8, 1921.

Application filed July 12, 1918. Serial No. 244,828.

To all whom it may concern:

Be it known that we, JOHN ISBISTER and JAMES CHAPMAN, subjects of King George V of Great Britain, residing at 40 Dowling street, Dunedin, in the Dominion of New Zealand, have invented certain new and useful Improvements in Hatpins, of which the following is a specification.

The object of the invention is to provide 10 a furcated pin with means thereon to clamp the prongs together so that they resemble one pin, for the purpose of facilitating their entry through the hat.

In the accompanying drawings, the figures 15 illustrate a bifurcated pin, and referring thereto,

Figure 1 is a view showing the clamping bead near the points of the pin, holding the prongs in a position so that they appear as 20 one pin, to facilitate their entry.

Fig. 2 is a view of the pin showing the clamping bead near the socket end of the prongs, the pin having been pushed through the said clamping bead to permit the prongs 25 to spring apart.

Fig. 3 is a part view of a pin showing a looped head with the clamping bead near the socket end of the prongs.

The following description, with reference 30 to the drawings, concerns a bifurcated pin, but if more than two prongs are wanted, more than one piece of wire must be used in the construction.

The hat pin is preferably constructed 35 from one piece of steel wire, the cross section thereof being approximately semi-circular, the wire having necessary resiliency, so that when bent at 1 to fit within the socket 2, the position of the prongs 3 and 4, 40 when not under the influence of the clamping bead 5, would be normally in the position illustrated in Fig. 2, but when under the influence of the said bead 5, the position of the prongs would be as indicated in 45 Fig. 1.

A suitable fastening is provided, such as 50 illustrated at 6, having one end attached to a lug 7 of the socket member 2, and the other end attached to a lug 8 of the clamping bead 5 to prevent the said bead from becoming disengaged; the clamping bead, the

fastening means, and the head 9 of the pin may be plain or ornamental to suit the taste.

In Fig. 3, the construction of the pin can be more readily traced as being formed from 55 one piece of wire; a loop 9^a is formed instead of employing a head 9. The prong members 3 and 4 where they project from the loop 9^a are brought closely together as indicated at 9^b, so that the prong members, 60 when not closed, as indicated in Fig. 2, under the influence of the clamping bead 5, would be held together at the neck of the pin by the transference of the said clamping bead member 5, to the neck, the said bead member 5 becoming an equivalent to the socket 65 2 illustrated in Figs. 1 and 2.

With the provision of the clamping bead 5, the entry of the points 10 of the pin through the hat is facilitated, and during 70 the progress of pushing the pin to the desired position, the said clamping bead 5 automatically shifts from the point of the pin illustrated in Fig. 1 to the position illustrated in Fig. 2, whereupon the prongs 75 spread through the hair and virtually become a substitution for two pins.

We are aware that it is old to provide a bifurcated hatpin having means for moving the bifurcations together and do not lay 80 broad claims to such structure but what we do claim and desire to secure by Letters Patent is:—

A hat pin comprising a pair of prongs formed from one piece of resilient material 85 substantially semi-circular in cross section, bent back upon itself intermediate its ends, a head arranged to receive and clench said bent portion, and a bead slidably mounted on said prongs and arranged to move said 90 prongs into engagement with one another to form a unitary substantially cylindrical member.

In testimony whereof we have hereunto set our hands in presence of two subscribing 95 witnesses.

JOHN ISBISTER.
JAMES CHAPMAN.
